BEAUTY MITTEN

Wanda Burke, New York, N. Y.

Application September 18, 1937, Serial No. 164,469

2 Claims. (CL 2—158)

This invention relates to a covering for the hand for use during the treatment of the skin of the hand whereby the ointment or lotion used is held in the desired place so as to secure the desired result.

5 An object of the invention is to provide a covering for the hand in the general form of a mitten which may be applied without any appreciable sliding or relative movement of the hand or the 10 covering.

Another object of the invention is to provide a covering that may be applied to the hand or removed without appreciably disturbing any ointment or lotion previously applied to the hand, the 15 structure being such that when in use it will not only cover the hand but will permit the thumb and fingers to relax so as to permit a normal flow of blood throughout the hand.

In the accompanying drawing:
20 Fig. 1 is a front view of a beauty mitten disclosing an embodiment of the invention;

Fig. 2 is a rear view of the structure shown in Fig. 1;

Fig. 3 is a sectional view through Fig. 1 approximately on the line 3—3.

The mitten shown in the drawing may be made from knit material or woven material as preferred, but preferably from light material which is yielding and also comparatively soft. The yarn 30 used in making the mitten may be silk, cotton, rayon, or other suitable material.

In forming the mitten there is provided a body 1 which at one end merges into the wrist section 2 and at the other end into a rectangular finger section or cot 3 which is closed at the end 4 as well as at the sides and back. Preferably integral with the body 1 are the thumb and little finger cots 5 and 6. From the drawing it will be seen that the thumb cot 5 extends from the side of the 40 mitten at an angle substantially equal to a forty-five degree angle from a longitudinal central line drawn through the mitten. Also the thumb cot 5 is closer to the wrist section 2 than the little finger cot 6. It will be noted also from Figs. 1 45 and 2 that the little finger cot 6 is at an appreciably less angle than the thumb cot. This is to permit the various fingers to properly relax.

The cot 3 is sufficiently large to permit the three first fingers to separate slightly if desired. 50 In case the thumb and all of the fingers are moved into contact with each other, there is a slight strain between all the fingers and thumb. This is particularly true of the thumb and little finger. In case the hand is laid on a flat support 55 and allowed to relax properly, it will be noted that

the thumb will move to almost a forty-five degree angle and the little finger will separate from the next finger. The construction and position of the cots 5 and 6 accommodate this automatic relaxing action of the hand. The three other fingers move slightly apart and particularly the first finger moves slightly away from the second finger. This action is accommodated by the width of the cot 3.

As shown in Fig. 2, the wrist part 2, body 1, and part of cot 3 are divided or formed with an opening extending from the wrist end of the mitten to substantially centrally of the cot 3. The sides of the opening are connected by a suitable slide fastener 7, although other fastening means could be used without departing from the spirit of the invention. If desired the opening and slide fastener could extend almost to the closed end 4, although ordinarily this is not necessary. However, the opening preferably extends beyond the 20 end of the thumb cot 5 and to a point almost equal to the end of the small finger cot 6. The idea of having a long opening of this kind is to permit the hand to be inserted into the mitten with substantially no relative sliding movement between the 25 hand and the mitten.

When using the mitten the hand is covered or treated as desired with a lotion or ointment and naturally the lotion or ointment is placed at the points desired or over the entire hand. It is desired that this lotion or ointment shall remain in place until it has performed its function. Where an ordinary glove is used there is a relative sliding movement between the hand and the glove. This will scrape off or move the ointment away 30 from the places to be treated. By the construction shown in the accompanying drawing the mitten is laid wide open and the three first fingers are loosely placed in the cot 3 while the thumb and little finger are inserted into the cots 5 and 6. 35 The side portions 8 and 9 of the body and associated sections are then folded over to a substantially closed position and the fastener 7 caused to function to complete the closing action and to hold the mitten in its closed position. By this 40 construction the wrist section 2 may be made to rather snugly fit the wrist without causing the removal of any of the ointment. However, the entire hand and part of the wrist are covered so that the bed clothes when the device is used at night 45 will not be soiled and yet the treatment will form its desired function. The treatment will also take place with the various parts of the hand including the fingers and thumb in a relaxed condition. While normally the hand in the mitten is allowed 50

to relax as much as possible, sometimes it may be necessary to grasp an object and when this occurs the thumb and little finger may be brought together readily for this purpose.

5 I claim:

1. A beauty mitten comprising a body merging at one end into a wrist section and at the other end into a substantially rectangular section having a closed end, said section being adapted to receive the first three fingers of the hand, a thumb cot at one side edge of the mitten extending at substantially a forty-five degree angle from the longitudinal center of the mitten, a little finger cot at the opposite edge of the mitten positioned further from the wrist part of the mitten than the thumb and extending from the mitten at an appreciably less angle than the thumb, said mitten at the front being open from the wrist end to substantially midway of said rectangular finger section and beyond the outer end of said thumb cot, and a disengageable fastener for disengageably securing together the mitten along said opening.

2. A beauty mitten for covering a hand and holding a lotion in place comprising a mitten structure having a substantially rectangular finger section closed at its outer end adapted to receive the first three fingers of the hand, a thumb cot at one side edge of the mitten extending at substantially a forty-five degree angle from the longitudinal center of the mitten, a little finger cot at the opposite edge of the mitten positioned further from the wrist part of the mitten than the thumb and extending from the mitten at an appreciably less angle than the thumb, said mitten at the front being open from the wrist end to substantially midway of said rectangular finger section and beyond the outer end of said thumb cot, and a slide fastener for closing said opening.

WANDA BURKE.
